UNITED STATES PATENT OFFICE.

ALPHA D. TUTTLE, OF WEST BARRINGTON, NEW HAMPSHIRE.

SHINGLING-BRACKET.

1,299,874.

Specification of Letters Patent.

Patented Apr. 8, 1919.

Application filed March 2, 1918. Serial No. 220,068.

To all whom it may concern:

Be it known that I, ALPHA D. TUTTLE, a citizen of the United States, residing at West Barrington, in the county of Strafford and State of New Hampshire, have invented new and useful Improvements in Shingling-Brackets, of which the following is a specification.

This invention relates to scaffolds, and 10 more especially to shingling brackets; and the object of the same is to produce a light, simple, inexpensive, and reliable structure of this kind which may be stored in small compass when not in use and which may be 15 used on roofs of a variety of pitch, for holding the staging boards while shingles and the like are being applied or perhaps while the chimney is being built or repaired.

This object is carried out by constructing 20 the bracket in the manner hereinafter more fully described and claimed, and as shown in the drawings wherein:—

Figure 1 is a perspective view of a portion of a roof with this improved bracket 25 placed thereon, the staging board being indicated in dotted lines.

Fig. 2 is a longitudinal sectional view 30 through the device on a much steeper roof, showing how the spur at the lower end of the brace enters the roofing boards when the bracket is used in this instance.

Fig. 3 is an enlarged perspective detail of the lower end of the brace.

In the drawings I have used the letter R 35 to designate the roof, upon which in Fig. 1 is shown already laid the lower course of shingles S, above which the roof is as yet only the boards to which the shingles are to be nailed. I speak of shingles, but of 40 course these elements might be slates, in which case there would have to be boards laid upon the courses of slates where the spurs referred to hereinafter occur, and these boards in that instance would have to be 45 suitably supported. However, my bracket is particularly intended for shingles, although I do not wish to be limited to its use. The bracket is composed of four parallel bars, whereof those numbered 1 and 2 50 may be called the side bars, and those numbered 3 and 4 the intermediate or central bars. The latter are disposed rather closely together, and the side bars are spaced therefrom quite a little distance as shown; and 55 transverse rungs 5 connect all bars, there being of necessity one rung at the top, a

number at the bottom, and possibly intermediate rungs throughout the entire length of the structure as seen in Fig. 1. Inserted into and depending from the lower faces of 60 the outside bars, and preferably near their lower extremities as shown, are spurs 6 of metal and of a proper size and length to stick into the roof boards or the lower course of shingles and support the entire bracket 65 upon the roof as shown in the drawings. I use these spurs in the side bars rather than in the intermediate bars, because the side bars are spaced apart the full width of the bracket, and therefore when the latter is 70 held by two of these spurs firmly engaging the roof or the lower course of shingles, it will not swing from side to side. To an extent Fig. 2 is a modification, in that this view shows additional spurs 7 depending 75 from the lower faces of the side bars at their upper ends, but these I do not always contemplate using. Or, if I use the upper spurs, I do not always contemplate using the lower spurs, because two sets of spurs 80 are not ordinarily necessary.

Pivottally mounted on the upper rung at the point 10 is an arm 11 which is of a width to be folded between the innermost bars when the structure is collapsed for 85 storage or transfer, and of a length about half that of the bars. The numeral 12 designates a brace, forked at its upper end as at 13 and pivotally mounted as at 14 on the lower end of the arm 11, this member 90 being a little wider than the space between the innermost bars 3 and 4 so that it will overlie them when the parts are folded together, and of a length to reach a little beyond the lower ends of the bars when the 95 parts are in this condition. The obvious purpose of the brace is to support the outer end of the arm, as seen in Figs. 1 and 2 of the drawings. Its lower end is reduced and shouldered as at 15, beyond which its extremity is continued into a narrow spur 16 which is preferably cut off oblique on its under side as seen at 17. This oblique face prevents the spur from embedding the roof boards or shingles when the parts stand as 100 seen in Fig. 2, whereas the shoulder always contacts with the upper edges of the intermediate bars 3 and 4. When, however, the bracket is applied to a steeper roof as seen in Fig. 2, and the brace 12 takes a different 110 angle with respect to the bars, the tip of its spur will project between them and beyond

their lower faces and into the roof slightly, just at a time when the use of an additional spur to support the bracket on the much steeper roof is necessary and much more desirable. At this time and at all times the shoulders 15 rest on the bars 3 and 4 while the projection or extension 16 rests on one of the lower rungs between these bars. The staging board S is now laid across the arm 10 11, and extends from one bracket to another in a manner well understood to experts in this art. When the device is not in use, the parts may be folded in an obvious manner. I do not wish to be limited to the materials 15 or proportions of parts, nor to details other than as herein set forth.

What is claimed as new is:—

The herein described shingling bracket comprising four parallel bars whereof the

innermost are disposed more closely together than the others, a series of transverse rungs extending through all bars, spurs depending from the lower faces of the outermost bars, an arm pivoted at its upper end on the uppermost rung, a brace 25 forked at its upper end and passing astride and pivoted to the lower end of the arm, and a reduced extension at the lower end of said brace producing shoulders to bear on the faces of the intermediate bars and a spur 30 at its extremity of a length to project below the lower faces of said bars when the brace stands at a considerable angle thereto, and undercut so as not to project below said faces at other times. 35

In testimony whereof I affix my signature.

ALPHA D. TUTTLE.
